(57) **CLAIM**

The ornamental design for a floating water ionizer, as shown and described.

DESCRIPTION

FIG. 1 is an isometric top-side view of a floating water ionizer in accordance with the claimed design;

FIG. 2 is a front view of a floating water ionizer in accordance with the claimed design;

FIG. 3 is a rear view of a floating water ionizer in accordance with the claimed design;

FIG. 4 is a right side view of a floating water ionizer in accordance with the claimed design;

FIG. 5 is a left side view of a floating water ionizer in accordance with the claimed design;

FIG. 6 is a top side view of a floating water ionizer in accordance with the claimed design;

FIG. 7 is a bottom side view of a floating water ionizer in accordance with the claimed design;

FIG. 8 is an isometric bottom-side view of a floating water ionizer in accordance with the claimed design; and,

FIG. 9 is an exploded isometric bottom-side view of a floating water ionizer in accordance with the claimed design. The broken line showing of the screw in FIGS. 7-9 is included for the purpose of illustrating and forms no part of the claimed design.
